BRUSH

Francis Alphonse Piron, Wausau, Wis.

Application July 18, 1940, Serial No. 346,204

7 Claims. (Cl. 15—165)

This invention relates to an improved expandable brush for cleaning the interiors of vessels having restricted neck portions such as bottles and jars and the like.

More particularly, it is an aim of the invention to provide an expandable brush including chains of brushes attached to a supporting rod in a manner so that a movement of the chains in one direction will expand the chains to bring the brushes thereof into engagement with the inner side of a vessel to be cleaned while the movement of chains in another direction will contract the chains relatively to the rod to permit the insertion or removal of the brush through a restricted neck portion of the vessel.

Still a further aim of the invention is to provide a construction of chain brush having cam means associated with certain of the links of the chain for directing the chains to expanded positions relatively to their supporting rods and means to provide a limited sliding movement of certain of the links relatively to certain of the other links to permit the cam portions to move into positions for co-acting engagement.

Still another object of the invention is to provide a construction of chain brush wherein the alternate links of the chain will carry the individual brush element and to so mount said brush element relatively to said links and each of the brush elements will be engaged by two of the links for retaining the individual links in extended positions relatively to each other when the chains are in operative positions.

Other objects and advantages of the invention will hereinafter become more fully apparent from the following description of the drawing, which illustrates a preferred embodiment thereof, and wherein:

Figure 1 is a side elevational view showing the invention in an expanded, operative position.

Figure 2 is an enlarged fragmentary longitudinal central vertical sectional view of a portion of one of the chains, and

Figure 3 is a longitudinal horizontal sectional view taken substantially along the plane of the line 3—3 of Figure 2.

Referring more particularly to the drawing, wherein like reference characters designate like or corresponding parts throughout the different views, 10 designates generally a cleaning brush comprising the invention and which includes a rod 11 to one end of which is fixedly secured a brush 12 which is disposed substantially at a right angle to the axis of the rod 11. A pair of corresponding chains, designated generally 13,

are each pivotally connected at one end thereof to the opposite ends of the head portion of the brush 12 at 14. The opposite ends of the chains 13 are each pivotally connected at 15 to a bar 16. The pair of bars 16 are slidably attached to the rod 11 by means of bands or rings 17 which combine therewith to form a sleeve member, designated generally 18, which is slidably mounted on the rod 11 to thereby provide means whereby one end of each of the chains 13 is fixedly connected relatively to the rod 11, while the opposite end of each of the chains 13 is slidably connected relatively thereto.

Referring particularly to Figures 2 and 3, the chains 13 are each composed of alternate links 19 and pairs of links 20. The links 19 are channel shaped and the sides of each of said links, at corresponding ends thereof, are beveled to form the downwardly and outwardly inclined cam faces 21. The said sides 22, at their opposite ends, are tapered to form the pointed projections 23. The sides 22 are also provided with oblong openings 24 which are disposed adjacent the ends 21 and substantially at right angles to said cam faces. As best seen in Figure 3, a pair of links 20 are rigidly connected, adjacent their corresponding ends, to the sides 22 of each of the links 19, and adjacent their ends 23 by means of nut and bolt fastenings 25. The opposite, free ends of the links of the pair project beyond the tapered ends 23 and are adapted to be connected to the opposite end of the next adjacent link 19 by means of a nut and bolt fastening 26 which extends through apertures in the free end of the links 20 and through the slots 24 of said last mentioned link 19. The shank of the bolt or fastening 26 is preferably provided with a sleeve 27 for slidably engaging the slots 24 through which it extends. It will thus be seen that the alternate links 19 are each fixedly connected at one end to a pair of links 20 and slidably and pivotally connected at its opposite end to another pair of links 20.

A brush 28 is carried by each of the links 19. The brushes 28 each includes a head portion 29 which is secured to the outer sides of a base portion 30 of a link 19 by means of a plurality of nut and bolt fastenings 31. The brush heads 29 are so connected to the base portions 30 that one end of the brush head 29 extends beyond the corresponding end of the base 30 while the opposite end of the base 30 projects beyond the opposite end of the brush head 29. The brush heads 29 are provided with outwardly projecting tufts of bristles which combine to form a bristle

portion 32 and the brush 12 is provided with a similar bristle portion 32. Due to the off-set connection of the base portions 30 and the brush heads 29, the exposed end of each of the base portions 30 is disposed in overlapping engagement with the exposed end of the brush head 29 of the next adjacent link 19, when the links 19 and 20 and the chains 13 are in extended positions relatively to each other, as illustrated in Figures 1 and 2.

Assuming the brush 10 to be in the position as seen in Figure 1, by moving the sleeve 18 away from the brush 12 the chains 13 will be drawn inwardly relatively to each other and into contracted positions relatively to the rod 11 so that the head portion of the brush 10 can be passed through a restricted neck 33 of a bottle or jar 34, shown in dotted lines in Figure 1, to thereby remove the brush 10 from the bottle or jar 34. In a like manner, the head portion of the brush 10 can be inserted into the bottle or jar 34 while the chains 13 are in a contracted position after which the sleeve 18 can be moved toward the brush 12 to expand the chains 13 to bring the bristle portions 32 of the brushes 28 thereof into engagement with the inner side of the jar 34 for scouring or scrubbing the interior of the jar 34 by turning it relatively to the brush 10. As the sleeve 18 is moved toward the brush 12 for expanding the chains 13, the links 20 will move inwardly relatively to the links 19 and through the slots and fastening connections 24 and 26 to cause the tapered ends 23 of each link 19 to contact the cam surfaces 21 of the next adjacent link 19, toward the fixed ends of the chains 13, to provide a cam engagement which will progressively urge the links 19 and 20 outwardly relatively to the rod 11 from the ends thereof which are secured to the brush 12 to their opposite ends. When the links 19 and 20 reach their fully expanded positions as defined by the vessel 34 in which the brush 10 is mounted, the exposed ends of the base portions 30 will move into overlapping engagement with the exposed ends of the brush heads 29 to position the links 19 and 20, in the manner as illustrated in Figures 1 and 2, to thereby cause the fastenings and sleeves 21 to move to the upper and outer ends of the slots 24 to position the links 19, which are disposed in a straight line, in extended positions relatively to each other. When thus positioned, the overlapping engagement of the base portions 30 and brush heads 29 will combine with the links 20 to prevent the individual links 19 from moving relatively to one another so that the brushes 28 carried thereby will be moved out of engagement with the vessel 34. As heretofore mentioned, the links of the chains 13 move from contracted to expanded positions progressively beginning with the links connected to the brush 12, and conversely, the links of the chains 13 progressively move to collapsed positions, when actuated by the movement of the sleeve 18 away from the brush 12, beginning with the links connected to the sleeve 18.

Various modifications and changes are contemplated and may obviously be resorted to as only a preferred embodiment of the invention has been disclosed.

I claim as my invention:

1. A device of the class described, comprising a rod, chains of brushes, each of said chains having an end pivotally connected to one end of the rod, a member slidably mounted on said

rod, the opposite ends of said chains of brushes being pivotally connected to said member, each of the chains of brushes including alternate links each comprising brush elements and alternately arranged connecting links, the connecting links each being rigidly attached at one end to an end of one brush element and slidably and pivotally attached at its opposite end to the adjacent end of another brush element, and the head portions of the brushes of the chains being constructed and arranged to overlap for holding the chains of brushes in expanded positions.

2. A device of the class described, comprising a rod, a chain of brushes having an end pivotally connected to one end of the rod, a member slidably mounted on said rod, the opposite end of said chain of brushes being pivotally connected to said member, links arranged between and connecting the individual brushes of the chain, each of said links being fixedly connected at one end to an end of one brush and slidably and pivotally connected at its opposite end to the adjacent end of another brush, and the head portions of the brushes of said chain having tapered corresponding ends and obliquely disposed cam faces at their opposite ends, said tapered ends being disposed to engage the cam faces for directing the brushes outwardly, relatively to the rod, when said member is moved toward the end of the rod to which the chain is secured, for moving the chain of brushes to an expanded position.

3. A device of the class described, comprising a rod, a chain of brushes having an end pivotally connected to one end of the rod, a member slidably mounted on said rod, the opposite end of said chain of brushes being pivotally connected to said member, links arranged between and connecting the individual brushes of the chain, each of said links being fixedly connected at one end to an end of one brush and slidably and pivotally connected at its opposite end to the adjacent end of another brush, and the head portions of the individual brushes of the chain being constructed and arranged to overlap, and the overlapping portions of the brush heads being provided to cooperate with said links for holding the chain of brushes in an expanded position.

4. A device of the class described, comprising a rod, a chain of brushes having an end pivotally connected to one end of the rod, a member slidably mounted on said rod, the opposite end of said chain of brushes being pivotally connected to said member, links arranged between and connecting the individual brushes of the chain, each of said links being fixedly connected at one end to an end of one brush and slidably and pivotally connected at its opposite end to the adjacent end of another brush, and the head portions of the brushes of said chain having tapered corresponding ends and obliquely disposed cam faces at their opposite ends, said tapered ends being disposed to engage the cam faces for directing the brushes outwardly, relatively to the rod, when said member is moved toward the end of the rod to which the chain is secured, for moving the chain of brushes to an expanded position, and the head portions of the individual brushes of the chain being constructed and arranged to overlap for holding the chain of brushes in an expanded position.

5. A device of the class described comprising a rod, chains each pivotally connected at one end to an end of the rod, a sleeve slidably

mounted on the rod, the opposite ends of the chains being pivotally connected to said sleeve, brushes and connecting links arranged to form alternate links of the chains, said connecting links having corresponding ends slidably and pivotally connected to corresponding ends of the brushes, and said brushes having co-acting cam portions for directing the connecting links and brushes outwardly relatively to the rod when the sleeve is moved in one direction for expanding the chains.

6. A device of the class described comprising a rod, chains each pivotally connected at one end to an end of the rod, a sleeve slidably mounted on the rod, the opposite ends of the chains being pivotally connected to said sleeve, brushes and connecting links arranged to form alternate links of the chains, said brushes being constructed and arranged for overlapping engage-

ment with one another for holding the connecting links and brushes in extended positions relatively to each other when the chains are expanded relatively to the rod.

5 7. A brush for cleaning the interior of vessels, comprising a rod, a plurality of alternately arranged and connected brushes and links forming a chain, one end of the chain being attached to an end of the rod, and a member slidably mounted on the rod and pivotally connected to the opposite end of the chain, said links being slidably and pivotally connected at corresponding ends to corresponding ends of the brushes and fixedly connected at their opposite ends to the opposite ends of the brushes, and said brushes having overlapping portions cooperating with the links for retaining the brushes in expanded positions relatively to the rod.
